UNITED STATES PATENT OFFICE.

ADOLF MESSE, OF FRANKFORT-ON-THE-MAIN, GERMANY.

METHOD FOR THE IGNITION OF BLASTING CARTRIDGES.

Application filed August 29, 1921. Serial No. 469,768.

(GRANTED UNDER THE PROVISIONS OF THE ACT OF MARCH 3, 1921, 41 STAT. L., 1313.)

To all whom it may concern:

Be it known that I, ADOLF MESSE, a citizen of the German Republic, residing at Frankfort-on-the-Main, Germany, have invented certain new and useful Improvements in Methods for the Ignition of Blasting Cartridges (for which I have filed an application in Germany August 16, 1915), of which the following is a specification.

For blasting with liquid air or liquid oxygen the priming of the explosive is prepared in such a manner that before the carbon cartridge or, if the charge consists of several cartridges, one of said cartridges is dipped into the liquid air or into the liquid oxygen, the fuze or quick match with a priming cap is attached to said cartridge. There are mostly several cartridges in the dipping vessel at the same time and the quick matches of all the cartridges which are being soaked hang over the rim of the vessel. When open lamps are used in the mines and also for many other reasons there is always a great danger of premature ignition of the cartridges in the dipping vessel.

These dangers are removed according to this process in a very simple manner.

A preferred form of apparatus by which the invention is carried into effect is illustrated in the accompanying drawing, wherein:—

Fig. 1 shows the application of the igniting method to a blast hole.

Fig. 2 shows on a larger scale than Fig. 1 the priming cartridge with a fuze in side elevation partly in section.

A short carbon cartridge, a cartridge filled with any other combustible substance, or a plug of incombustible material which may serve as tamping is connected with the fuze or quick match which can have been fitted previously with the primer. This priming cartridge or plug is not dipped into liquid air or liquid oxygen.

The carbon cartridges which have been impregnated with liquid air or with liquid oxygen are, for safety against premature ignition, provided with strings or cords which have been rendered incombustible. In or-

der to make the blasting charge ready one or several carbon cartridges p^1 , p^2 (Fig. 1) impregnated with liquid air or with liquid oxygen are inserted in the blast hole, whereupon a not impregnated priming cartridge e or a plug prepared for priming and finally the tamping d are inserted. The priming cartridge (Fig. 2) is pushed in close contact with the impregnated carbon cartridges. This priming cartridge consists of the priming plug a to which the fuze b of incombustible material is attached and of wooden rollers c which serve to facilitate the insertion of the priming plug into the blast hole and to ensure the accurate position of the same in front of the carbon cartridges p^1 , p^2 . The fuze b has not been dipped into liquid air or liquid oxygen as stated above. The electric lead f (Fig. 1) is attached to the fuze b . The oxygen vapours which are produced penetrate into the priming cartridge up to the ignition so that this priming cartridge is thoroughly impregnated with these vapours so that this priming cartridge has been transformed before the priming takes place, into a blasting cartridge and causes by its own rapid combustion also a rapid combustion of the entire blasting charge.

When a priming plug is used which can serve at the same time for tamping the blast hole the quick match or the priming cap are arranged so that they are in contact with the impregnated carbon cartridge whereby the same is ignited.

I claim:—

1. An improved method for the making ready and for the ignition of blasting cartridges of combustible material and liquid oxygen or liquid air consisting in inserting the priming device into the blast hole with a separate support which is not impregnated instead of dipping the same into the liquid together with the carbon cartridge in order to prevent premature ignition or mis-firing.

2. An improved method for the making ready and for the ignition of blasting cartridges of combustible material and liquid oxygen or liquid air consisting in inserting

the priming device into the blast hole with a separate support which consists of an in-combustible substance and is not impregnated instead of dipping the same into the liquid together with the carbon cartridge in order to prevent premature ignition or mis-firing.

In testimony whereof I affix my signature in presence of two witnesses.

ADOLF MESSER.
